CARL KASPAR, OF CHICAGO, ILLINOIS.

TROLLEY MECHANISM FOR RAILWAY-CARS.

1,238,148.

Specification of Letters Patent. Patented Aug. 28, 1917.

Application filed October 11, 1912, Serial No. 725,213. Renewed January 22, 1917. Serial No. 143,843.

To all whom it may concern:

Be it known that I, CARL KASPAR, a subject of the Emperor of Austria, residing at Chicago, in the county of Cook and State of Illinois, have invented certain new and useful Improvements in Trolley Mechanism for Railway-Cars, of which the following is a specification.

My invention relates to trolley mechanism for electric railway cars, and has reference more particularly to a new and improved mechanism for operating and controlling the trolley-wheel carrier, and facilitating the finding of the wire by the motorman or conductor from either end of the car. Many so-called trolley wire finders have been proposed, but the same have been used to but slight extent, if at all, because of such limited capacity as to be of little practical use.

Among the salient objects of my present invention, are, to provide a trolley mechanism that shall be capable of operation by the motorman or conductor from either end of the car without leaving the latter; to provide a trolley mechanism wherein the operator shall have perfect control of the trolley-wheel carrier and wheel during both vertical and lateral movements of the latter so as to readily enable the wheel to be guided directly into contact with the wire; to provide an improved trolley mechanism wherein the vertical and lateral oscillations of the trolley-wheel carrier may take place without any interference with or hindrance from the operating mechanism of said carrier; to provide a mechanism wherein the trolley-wheel carrier may be readily drawn down and automatically locked in lowered position when desired, as when the car is to be sent into the barn; and to provide a trolley mechanism which will obviate the slipping of the trolley-wheel off the wire and insure its remaining in continuous touch with the wire irrespective of speed, and curvature and unevenness of the track.

My invention, its mode of operation, and its advantages will all be readily comprehended when considered in connection with the accompanying drawings, in which I have illustrated one practical mechanical embodiment of the same and in which—

Figure 1 is a vertical longitudinal section through the roof and upper portion of an electric car showing my improved mechanism in side elevation as applied thereto. Fig. 2 is a cross section on the line 2—2 of

Fig. 1. Fig. 3 is an enlarged detail plan view, partly in horizontal section, of a portion of the contact frame operating mechanism through or by which accommodation is made for the vertical vibration of said frame when in service. Fig. 4 is a side elevation of the winding drum and its gear, showing also a spiral spring within said drum through the agency of which the operating cable of the contact frame is maintained taut under the vertical vibrations of said frame. Fig. 5 is a detail top plan view of a crank disk and locking mechanism therefor that is located on the platform of the car and constitutes the initial element of the contact frame operating mechanism. Fig. 6 is an enlarged view, partly in section and partly in side elevation of the crank disk and locking mechanism shown in Fig. 5. Fig. 7 is a detail top plan view of the crank disk locking pin and its support as shown in Fig. 6. Fig. 8 is an enlarged detail elevation of a portion of the mechanism for operating and controlling the lateral or side swinging movements of the trolley contact frame.

Referring to the drawings, 10 designates a rectangular frame-casting secured to the underside of a car roof 11, preferably at the longitudinal center of the latter, and having on its upper side a pair of ears 12 in which is pivotally mounted, on an axis extending lengthwise of the car, an auxiliary frame 13. Journalled in bearings 14 of said auxiliary frame, the axes of which extend transversely of the car, are the lower arms 15 of a trolley contact frame of the lazy tongs type, the upper arms 16 of which are forked and pivotally connected at their upper ends and carry a trolley wheel 17 adapted to engage the usual overhead trolley wire 18. The lower arms 15 are connected, near their lower ends, by a strong tension spring 19 which normally tends to expand the contact frame and keep the trolley wheel in engagement with the wire.

Within the main frame 10 is mounted a fixed horizontal shaft 20 (Fig. 3) on which is loosely mounted a hollow drum 21 having a spirally grooved periphery 22 to which is attached a cable 23 adapted to wind and unwind on said drum, said cable extending upwardly through the frames 10 and 13 and the roof of the car, and attached at its upper end to the upper joint of the trolley contact frame. When the cable 23 is wound up on

the drum 21, the trolley contact frame is collapsed and the wheel 17 disengaged from the wire 18. Conversely, when the drum turns in the opposite direction, the cable unwinds and the trolley contact frame expands under the action of spring 19.

The expanding and contracting movements of the trolley contact frame are effected and controlled from the ends of the car by mechanism within convenient reach of the motorman or conductor on the platforms. This operating and controlling mechanism includes a lost-motion mechanism which accommodates the vertical vibratory motion of the trolley contact frame that always occurs owing to variations in the distance between the trolley wire 18 and the roof 11 of the car and the variations in the load effect of the trolley wire on the contact frame at different points along the route.

As so much of the operating and controlling mechanism as extends from the ends of the car to the central frame-casting 10 is in duplicate at the two ends of the car, the duplicate parts of this mechanism will be described and identified by the same reference characters. Journaled in bearings in the opposite end walls of the frame casting 10 and in hanger brackets 24 secured to the roofs of the end platforms are a pair of shafts 25. The outer end of each shaft is geared by bevel pinions 26 and 27 to the upper end of a vertical shaft 28 journaled in the bracket 24 and in an inwardly extending bracket 29 secured to the outer end wall of the car platform. Keyed to the lower end of shaft 28 is a crank disk 30 provided with an operating handle 31.

Referring now more particularly to Figs. 3 and 4, which show the lost-motion mechanism for accommodating the vibratory expanding and contracting movements of the trolley contact frame when in service, and which lost-motion mechanism constitutes a part of the complete mechanism for collapsing the contact-frame and controlling its expanding movement into engagement with the trolley wire, 32 designates a helical spring housed within the hollow winding-drum 21, said spring being secured at its outer end 33 to the inner periphery of said drum and at its inner end 34 to the fixed shaft 20 on which the drum is mounted. The spring 32 is lighter than the spring 19, and normally tends to turn the drum in a direction to wind the cable 23 thereon. Fast with one side of the drum 21 is a spur gear 35 that meshes with a spur gear 36 carried by a hub member 37. The inner end portion of one of the shafts 25 lying within the frame casting 10 is formed with a screw-thread 38 that extends entirely through the hub member 37, the extreme inner end of

said shaft 25, beyond said threaded portion, 65 38, having a bearing in an inwardly projecting stud 39 of the frame casting 10. Slidably mounted within the hub 37, and splined thereto, as shown at 40, is an internally threaded sleeve 41 that engages the threaded portion 38 of the shaft 25. Fast 70 on the hub member 37, and preferably integral or fast with the inner face of the spur gear 36, is a bevel gear 42 that meshes with an idler bevel gear 43 journaled on the stud 39. The idler gear 43 in turn meshes with a bevel gear 44 that corresponds with the bevel gear 42 but turns in the opposite direction, and is itself fast on a hub member 45 corresponding with the hub member 37. 75 Said hub member 45 contains an internally threaded sleeve 46 splined thereto at 47 and corresponding with the sleeve 41, said sleeve 46 engaging a similar threaded portion 48 of the other shaft 25, the extreme inner end 80 of which is also journaled in the stud 39 opposite the extreme inner end of its companion shaft 25. Between the outer end of the hub 37 and the adjacent side wall of the frame casting 10 is a bearing ring or washer 49, and between the outer end of hub 45 and the opposite side wall of the frame casting 10 is a similar bearing ring or washer 50. Keyed to each of the shafts 25 within the washers 49 and 50 is a collar 51 formed on its inner face with a tooth 52 adapted to engage a coöperative tooth 53 on the outer end of each of the threaded sleeves 41 and 46 when the latter are at the extreme of their outward travel on their respective screws 38 and 48; the purpose of said coöperating teeth being to effect a positive driving clutch-engagement between the shafts 25 and the sleeves 41 and 46.

The parts of the mechanism shown in Fig. 3 occupy substantially the relative positions therein illustrated when the trolley contact-frame is in the service position shown in Fig. 1, the cable 23 being then substantially unwound from the drum 21. Assuming that it is desired to completely collapse the trolley contact-frame from the left-hand end of the car shown in Fig. 1, the handle 31 is grasped and the crank disk 30 turned continuously in one direction. During the first part of this turning movement the sleeve 41 feeds inwardly on the screw 38 until the tooth 52 catches the tooth 53, whereupon the rotative movement of the shaft 25 is then transmitted to the hub 37, gear 36, coöperating gear 35, and drum 21, thus winding up the cable 23 and collapsing the contact-frame. As soon as the rotative movement of hub 37 and gear 36 has begun, this movement is transmitted through idler gear 43, bevel gear 44, hub 45 and spline 47, to the mating sleeve 46, which simply causes the latter to feed idly.

outwardly on its screw 48 during the winding up of the cable 23. When the cable 23 is to be unwound to allow the contact-frame to expand and move the trolley wheel 17 into engagement with the trolley wire 18, the crank disk 30 is turned in the opposite direction. During the first part of such turning movement, the spring 19 and trolley contact-frame unwind the cable 23 from the drum 21, but during this unwinding of the cable the sleeve 41 remains stationary relatively to its screw 38, since the two are rotating in the same direction and at the same speed. During this part of the back turning movement, however, the opposite sleeve 46 is fed back inwardly of its screw 48 to the position shown in Fig. 3. As soon, now, as the wheel 17 has found the wire 18, and the contact-frame is balanced against the wire, there is no further rotative movement of the drum 21 and the parts geared thereto; but the back turning movement of the crank disk 30 is continued beyond that point until the sleeve 41 is fed outwardly of its screw 38 to the normal operative position shown in Fig. 3.

The parts operate in precisely the same manner when actuated from the other end of the car; the only difference being that, in this case, the sleeve 46, hub 45, and bevel gears 44, 43 and 42 are active driving members, instead of idlers, while the sleeve 41 is idly shifted outwardly and then inwardly of its screw in the same manner as described with reference to the sleeve 46.

When the parts are in the normal operative position shown in Figs. 1 and 3, the helical spring 32, the tendency of which is to wind the cable 23 on the drum 21, keeps the cable 23 taut and relieves the trolley wire 18 of undue upward pressure resulting from the expanding tendency of the contact-frame under the action of the stronger spring 19. During the vertical vibratory movements of the contact-frame, the sleeves 41 and 46 merely play outwardly and inwardly slightly upon their respective screws, without exerting any appreciable turning effect upon the long transmission shafts 25 and their actuating mechanism at the ends of the car. The threaded inner portions of the shafts 25, the sleeves 41 and 46, and the gearing connecting the same, thus constitute in effect, a lost-motion mechanism included within the operating mechanism of the trolley contact-frame that readily accommodates the vertical vibratory motions of the latter in service without transmitting the same throughout the entire operating mechanism. In this connection it may be noted that the operating teeth 52 and 53 are not indispensable, since they might be omitted without affecting the described operation; but they are prefer-

ably employed in order to prevent undue jamming of the outer ends of the sleeves 41 and 46 against the collar 51, which might interfere with the freedom of the unwinding movement of the cable drum. The collars 51, are, of course, so set on their respective shafts that the coöperating teeth will couple just at the limit of the inward movement of the sleeves.

With such a mechanism as that above described, it is desirable to provide a means for determining and limiting the exact required turning movement of crank disk 30, as well as for locking the latter at the two extremes of such turning movement. This may be effected in various ways, but in Figs. 5, 6 and 7, I have illustrated a simple mechanism for securing this result.

Referring to said drawings, it will be noted that in the upper face of the crank disk 30 is formed a spiral groove 54, and on its lower face is formed a narrow diametric slot 55, in which is slidably mounted a latch-bar 56 supported on pins 57 extending across the slot 55 and engaging a slot 58 in said latch-bar. The upper edge of the outer end portion of the latch-bar 56 intersects on a radial line the bottom of the spiral groove 54, as shown in Fig. 6 and said upper edge is formed with a pair of outer and inner cam notches 59 and 60, respectively, that co-operate with a locking-pin 65 hereinafter referred to. The latch-bar 56 is normally forced outwardly by a spring 61, and is adapted to be manually drawn inwardly, when the handle 31 is grasped, by a trigger 62.

In the bracket 29 is formed a horizontal slot 63, in which is slidably mounted a locking-pin housing 64 carrying a spring-pressed locking-pin 65, the lower end of which travels in the spiral groove 54 and is normally pressed downwardly. Fig. 6 shows the parts in the positions which they occupy when the contact-frame is in the expanded position (Fig. 1). Upon collapsing the contact-frame as hereinbefore described, the handle 31 is grasped, the trigger 62 drawn toward the handle whereupon the cam notch 60 forces the locking-pin 65 upwardly flush with the bottom of the groove, whereby the crank disk 30 is released, and the latter is then turned continuously in one direction until the locking-pin snaps down into the notch 59, the latch-bar 56 having been released during the turning movement. The crank disk 30 is thus positively locked at both extremes of its turning movement, thus holding the shaft 25 locked against possible oscillation under the vibratory movements of the contact-frame; and the length of the spiral groove 54 between the inner and outer locking points 60 and 59 is made to accurately conform with the re-

quired extent of turning movement of the crank disk in order to effect the described operation of the mechanism and insure an intermediate position of the sleeves 41 and 46 on their respective screws.

It is, of course, necessary, when employing a contact-frame of the type herein shown, to provide means for effecting the lateral swing of said frame when moving the wheel into engagement with the wire, as well as for permitting lateral vibration of said frame in service. The pivoting of the auxiliary frame 13 on a longitudinal axis in the bearings 12, of course, permits such lateral movement of the contact-frame, and its lateral movement is regulated by a pair of springs 66 (Fig. 2) anchored at their lower ends to the decks of the car roof and at their upper ends connected to laterally extending arms 67 on the auxiliary frame 13. The outer ends of the arms 67 are preferably connected to the deck of the roof by jointed links 68, which aid somewhat in steadyng the contact-frame and serve to limit the extreme lateral swing of the latter, although said links are not essential, and may be dispensed with if desired. To the outer ends of the arms 67 are connected a pair of operating cables 69, as shown in Fig. 8, each of said cables extending from the end of one of the arms 67 downwardly through a hole 70 in the deck of the car, thence around a horizontally journaled pulley 71 carried by a bracket 72 secured to the under side of the deck of the car, thence to the outer end of the car vestibule and over a pair of vertically journaled pulleys 73 (Fig. 2), supported by brackets 74 secured to the roof of the vestibule, thence back over a pulley 71 on the opposite side of the car, and thence upwardly to the outer end of the other arm 67. To the outer end wall of the vestibule is pivoted an operating lever 75, the upper end of which is made fast to that portion of the cable 69 that extends between the pulleys 73. It will be manifest that by swinging the lever 75 to one side or the other, the trolley contact-frame will be swung laterally in the same direction as the lower arm of the lever 75.

In order that the motorman, from his position in the car vestibule, may be able to guide and direct the expanding movement of the contact-frame when throwing the trolley-wheel onto the wire, it is necessary to provide means for enabling him to observe the movements of said contact-frame during this operation. For this purpose I provide a mirror suitably positioned to reflect the image of the contact-frame to the eye of the motorman. This mirror may be mounted on the vestibule in any suitable or desired manner to secure the results stated; but preferably I provide a mirror, such as is indicated at 76 in Fig. 1 that is hinged at 77 to the

roof of the vestibule just above the end wall thereof, and lies above and normally covers an opening 78 in the roof of the vestibule. The mirror 76 may conveniently be raised to a suitable angle to reflect the image of the contact-frame and trolley-wheel to the eye of the motorman by an operating device comprising a vertically movable operating rod 79 slidably mounted in guides 80 on the end wall of the vestibule and connected to the mirror-frame by pivoted links 81. The operating rod 79 has an inwardly-bent lower end 79' to form a handle, and may be retained in adjusted position by a friction spring 82. In this way the mirror is conveniently mounted in a favorable position to perform its function; and, when not in use, constitutes a closure for the opening 78, preventing the entrance of rain, as well as protecting the reflecting face of the mirror from exposure to the elements when not in service.

The operation of the apparatus has already been indicated in construction with the description of its construction. It will be evident that the operating parts are all within easy manipulation and control by the motorman from his position on the end platform of the car; that the contact-frame, when collapsed, is automatically locked in collapsed position; that the cable 23 is automatically maintained taut during the vibrations of the contact-frame; that the motorman, by operating the crank disk 30 with one hand and the lever 75 with the other, is able to move the trolley-wheel 17 directly and accurately into engagement with the wire 18, without having to fish for the latter; and that the manipulation of the trolley contact-frame is thus placed under the control of the motorman, relieving the conductor of the car of that duty.

Although I have herein illustrated and described a trolley-wheel carrier having the form of a contact-frame of the lazy-tongs type, it will be evident that this specific form of trolley-wheel carrier is not essential to the carrying out of my invention in its broader aspects, but may be substituted by any other form or type of trolley-wheel carrier capable of up-and-down movements or up-and-down and lateral movements on its support.

It will be manifest to those skilled in the art that the described mechanism may otherwise be modified in respect to details without involving any departure from the principles involved or sacrificing any of the benefits and advantages of the invention. Hence I do not limit the latter to the particular mechanism disclosed except to the extent clearly indicated in specific claims.

I claim—

1. The combination with a car body, of a trolley-wheel carrier mounted thereon, a

- spring normally tending to elevate said carrier, a winding-drum, a cable connected to said winding-drum and to the upper portion of said carrier, a spring lighter than said carrier-raising spring normally tending to turn said drum in a direction to wind said cable thereon, and drum-winding mechanism extending from said drum to an end platform of the car.
2. The combination with a car body, of a trolley-wheel carrier mounted thereon, a spring normally tending to elevate said carrier, a winding-drum, a cable connected to said winding-drum and to the upper portion of said carrier, a spring lighter than said carrier-raising spring normally tending to turn said drum in a direction to wind said cable thereon, and drum-winding mechanism extending from said drum to an end platform of the car, said drum-winding mechanism including a lost-motion mechanism permitting freedom of oscillation of said drum under the vertical vibration of said carrier.
3. The combination with a car body, of a trolley-wheel carrier mounted thereon, a spring normally tending to elevate said carrier, a winding-drum, a cable connected to said winding-drum and to the upper portion of said carrier, a spring lighter than said carrier-raising spring normally tending to turn said drum in a direction to wind the cable thereon, an operating shaft extending from the vicinity of said winding-drum to an end platform of the car and having a threaded inner end, an internally threaded sleeve engaging the threaded inner end of said operating shaft, and a gear connection between said sleeve and drum having splined engagement with said sleeve.
4. The combination with a car body, of a trolley-wheel carrier mounted thereon, a spring normally tending to elevate said carrier, a winding-drum, a cable connected to said winding-drum and to the upper portion of said carrier, a spring lighter than said carrier-raising spring normally tending to turn said drum in a direction to wind the cable thereon, a pair of longitudinally alined operating shafts extending from the vicinity of said winding-drum to the end platforms of the car, respectively, and having threaded inner ends, internally threaded sleeves engaging the threaded inner ends of said operating shafts, a gear-train between and having splined engagement with said sleeves, and a gear connection between one member of said gear-train and said drum.
5. The combination with a car body, of a trolley-wheel carrier mounted thereon, a spring normally tending to elevate said carrier, means, including a lost-motion mechanism, for lowering said carrier extending from the latter to an end platform of the car and terminating in a crank disk, and means for automatically locking said crank disk against further turning movement in either direction when the carrier has been fully lowered.
6. The combination with a car body, of a trolley-wheel carrier mounted thereon, a spring normally tending to elevate said carrier, means, including a lost-motion mechanism, for effecting the downward movement and controlling the upward movement of said carrier extending from the latter to an end platform of the car and terminating in a crank disk, and means for automatically locking said crank disk against further turning movement in either direction when the carrier has been fully raised or lowered.
7. The combination with a car body, of a trolley-wheel carrier mounted thereon, a spring normally tending to elevate said carrier, means, including a lost-motion mechanism, for effecting the downward movement and controlling the upward movement of said carrier extending from the latter to an end platform of the car and terminating in a crank disk, said crank disk having a spiral groove in one face thereof with locking holes in the ends of said groove, and a spring-pressed locking pin engaging said groove and mounted to have sliding movement transversely of said groove.
8. The combination of a car body, a trolley adapted to be raised and lowered to permit vertical movement thereof with reference to said car body, a spring normally tending to elevate said trolley, and a raising and lowering connection, manually controlled, and extending to each end of said car body, said means including a lost motion mechanism for permitting the normal vertical movement of said trolley under the influence of said spring.
9. The combination of a car body, a laterally movable trolley adapted to be raised and lowered to permit vertical movement of said trolley with reference to said car body, a spring normally tending to elevate said trolley, a raising and lowering manually controlled connection extending to either end of said car body, a lost motion mechanism interposed between said raising and lowering connections and said trolley, said raising and lowering manually controlled connections being adapted to be locked in position positively to hold down said trolley and adapted to be locked in another position permitting the elevation of said trolley by virtue of said lost motion mechanism, and means for locking said manually controlled connections in either of said positions at either end of said car.
10. The combination of a car body, a laterally movable trolley adapted to be raised and lowered to permit vertical movement of said trolley with reference to said car body, a spring normally tending to elevate

- said trolley, a raising and lowering manually controlled connection extending to either end of said car body, a lost motion mechanism intersposed between said raising and lowering connections and said trolley, said raising and lowering manually controlled connections being adapted to be locked in position positively to hold down said trolley and adapted to be locked in another position
- 10 permitting the elevation of said trolley by means of said lost motion mechanism, means for locking said manually controlled connections in either of said positions at either end of said car, and means operating in conjunction with said lost motion mechanism for positively effecting a lateral movement of said trolley.
11. The combination of a car body, a trolley-support vertically extensible and pivoted to swing in a plane crosswise of the car body, manually controlled connections extending to and operable from either end of said car for lowering said trolley, a spring and a lost motion mechanism operating in conjunction therewith for automatically elevating said trolley and permitting free up-and-down vertical movement of said trolley with reference to said car body when said manually controlled connections are
- 20 placed in a certain position, and means for locking said manually controlled connections in another position so as to overcome and prevent the operation of said spring and said lost motion mechanism and effect the holding down of said trolley.
12. The combination of a car body, a trolley-support vertically extensible and pivoted to swing in a plane crosswise of the car body, manually controlled connections
- 25 extending to and operable from either end of said car for lowering said trolley, a spring and a lost motion mechanism operating in conjunction therewith for automatically elevating said trolley and permitting
- 30 free up-and-down vertical movement of said trolley with reference to said car body when said manually controlled connections are placed in a certain position, means for locking said manually controlled connections in
- 35 another position so as to overcome and prevent the operation of said spring and said

lost motion mechanism and effect the holding down of said trolley, and means operating in conjunction with said lost motion mechanism for positively effecting a lateral 55 swinging movement of said trolley while permitting normal free swinging movement of said trolley to allow for lateral irregularities of the trolley wheel.

13. The combination of a car body, a contact device, means for supporting said contact device above the car body, a spring normally tending to elevate said contact device, a manually controlled connection for lowering the contact device extending from said 60 supporting means to an end platform of the car, a lost motion device associated with said manually controlled connection and permitting free up-and-down movement of said contact device under the influence of said 65 spring when said manually controlled connection is set in a certain position, means for operating said manually controlled connection to effect a lowering of the contact device against the influence of said spring, and 70 means for effecting a lateral movement of said contact device.

14. The combination of a car body, a contact device, means for supporting said contact device above the car body, pivoted on 80 said car body to swing as a whole in a direction crosswise of the car body, a spring normally tending to elevate said contact device, a manually controlled connection for lowering the contact device extending from said 85 supporting means to an end platform of the car, a lost motion device associated with said manually controlled connection and permitting free up-and-down movement of said contact device under the influence of said 90 spring when said manually controlled connection is set in a certain position, means for operating said manually controlled connection to effect a lowering of the contact device against the influence of said spring, 95 and means for effecting a lateral swinging movement of said contact device.

CARL KASPAR.
